Primary Examiner — Mark Goodwin(74) *Attorney, Agent, or Firm* — Finnegan, Henderson, Farabow, Garrett & Dunner LLP(57) **CLAIM**

The ornamental design for a deflector for paving apparatus, as shown and described.

DESCRIPTION

FIG. 1 is a perspective view of a deflector for paving apparatus showing our new design;

FIG. 2 is a rear perspective view thereof;

FIG. 3 is a front view thereof;

FIG. 4 is a rear view thereof;

FIG. 5 is a right side view thereof, the left side being a mirror image thereof; and,

FIG. 6 is a top plan view thereof, the bottom plan view being identical.
